UNITED STATES PATENT OFFICE.

FREDERICK A. FELDKAMP, OF UNION, NEW JERSEY, ASSIGNOR TO ELECTROLYTIC PRODUCTS COMPANY, A CORPORATION OF NEW JERSEY.

RADIATOR AND RADIATOR-SECTIONS THEREFOR FOR AUTOMOBILES AND THE LIKE.

1,108,495.

Specification of Letters Patent. Patented Aug. 25, 1914.

Application filed March 12, 1910. Serial No. 548,756.

To all whom it may concern:

Be it known that I, FREDERICK A. FELDKAMP, a citizen of the United States, residing at Union, in the county of Union and State of New Jersey, have invented certain new and useful Improvements in Radiator and Radiator-Sections Therefor for Automobiles and the like; and I do hereby declare the following to be a full, clear, and exact description of the invention, such as will enable other skilled in the art to which it appertains to make and use the same, reference being had to the accompanying drawings, and to characters of reference marked thereon, which form a part of this specification.

This invention has reference, generally, to improvements in radiators and radiator-sections therefor which are used more especially upon automobiles, motor-cars, and vehicles of similar character, but which may be employed also with other classes of machinery and apparatuses where it is desirable to cool liquids and fluids of the various kinds, or in which the operation may be reversed, the device in that case being used for heating fluids and the like.

The present invention has for its principal object to provide a novel and simple construction of radiator and radiator-section therefor of the general character herein-after more particularly set forth, and the various parts of each radiator-section comprising an electrolytically deposited structure made in one integral piece, and each section consisting of a multiplicity of hollow or tubular elements, interspersed with a multiplicity of holes or openings through which is permitted a free circulation of air or other cooling medium which is brought in contact with the outer surfaces of the said hollow or tubular elements, and the solid metal parts being of such thinness and being located so closely with relation to each other, that it is impossible to produce the radiator-sections by the usual process of casting.

Other objects of this invention not at this time more particularly mentioned, will be clearly understood from the following detailed description of the present invention.

With the various objects of this invention in view, the said invention consists, pri-

marily, in the novel and electrolytically produced radiator, and radiator section therefor, of the general character herein-after set forth; and, the invention consists, furthermore, in the novel arrangements and combinations of the various parts more particularly described in the following specification, and then finally embodied in the clauses of the claims which are appended to and which form an essential part of this specification.

The invention is clearly illustrated in the accompanying drawings, in which:

Figure 1 is a front view of a radiator showing one embodiment of the principles of the present invention, representing the front radiator-section partly in elevation and partly in vertical section; and Fig. 2 is a rear face view of the radiator. Fig. 3 is a transverse vertical section of portions of the radiator, said section being taken on line 3-3 in said Fig. 1, said view being made on an enlarged scale, and said view showing a radiator made up of an arrangement of three radiator-sections. Fig. 4 is a horizontal section taken on line 4-4 in said Fig. 1, and Fig. 5 is a similar section taken on line 5-5 in said Fig. 1, both of said sections being made on an enlarged scale.

Similar characters of reference are employed in all of the above described views to indicate corresponding parts.

Referring now to the said drawings, the reference-character 1 indicates a complete radiator-section, made according to and embodying the principles of the present invention, and all of the parts of which, except certain duct or pipe-like elements, which are to be used with the complete radiator, being made in one integral piece, the metal portions being made by electrolytical deposition. Each electrolytically deposited radiator-section, of which there may be one or more, according to the size and kind of radiator to be produced, consists of a hollow body or shell formed by the front face 2, the rear face 3, the top 4, the bottom 5, and the side-portions or ends 6. As shown, the front and rear faces 2 and 3 of the said hollow shell are provided with oppositely disposed openings 7 of any desirable configuration, the

2

said openings in practice being rather small, and a great many of such openings being used. Within the space 8 of the said body or shell 4, between the inner face of the front 5 2 and the rear 3, and surrounding each opening 7, are thin walls 9, the said walls being arranged in such close proximity to each other, so that in addition to forming with the said holes or openings 7 suitable 10 ventilating ducts or passageways, the said walls will form a number of diagonally disposed ducts or hollow portions, as 10 and 11, which cross each other, substantially as illustrated in Fig. 1 of the drawings. These 15 ducts or hollow portions 10 and 11 provide a multiplicity of waterways or passages, through which the water which is to be cooled, as for instance in automobile radiators, flows circuitously from the upper 20 water-space within each radiator-section, into and through the marginal side-spaces and the bottom-space from between the walls of each radiator-section, as will be clearly understood. The said front and end-walls 25 of each radiator-section are also provided in the upper portion of the space 8 with suitably disposed stays or reinforcing posts, as 12 and 13, and in the lower portion of the said space 8 with suitably disposed stays or 30 reinforcing posts, as 14 and 15, the said stays 12, 13, 14 and 15 being preferably made hollow, as shown, and forming integral parts of the said walls 2 and 3. The said stays or 35 members or elements, as 16, which extend laterally across the space 8, and are connected with the said walls 2 and 3, so as to form integral portions thereof. The said members or elements 16 are also made with 40 a plurality of holes or perforations 17 which provide suitable inlets for the purposes to be presently more fully set forth. In like manner, the said stays or posts 14 surround or encircle other tubular members or elements 18, similar to the members or elements 16, said members or elements 18 extending laterally across the lower portion of the space 8 and being connected with the said walls 2 and 3, so as to form integral portions 45 of the said walls. The said members or elements 18 are also made with a plurality of holes or perforations 19 which provide suitable outlets, for the purposes to be presently described.

50 55 In the upper portion of each radiator-section there are usually two of such tubular members or elements 16, while in the lower portion of each radiator-section there are usually three of such tubular members or 60 elements 18. From an inspection of Fig. 3 of the drawings, it will be evident, that in the extreme upper portion of each radiator-section, and extending across the space between the walls 2 and 3, is another tubular 65 member or element 20, said member or ele-

ment 20 being also connected with and forming an integral part of said walls 2 and 3. The said member or element 20 is also made with a plurality of small holes or perforations 21 which provide suitable inlets for 70 the purposes to be presently more fully specified.

As shown more particularly in Fig. 3 of the drawings, it will be seen that the thin connecting walls 9, by means of which the diagonal arrangement of conveying ducts or passageways 10 and 11 are provided, and the laterally extending cooling passages or ventilating ducts are formed, are angularly arranged, as at 22 and 23, so that tapering 75 openings which are of larger cross-section at the front and rear faces of the said radiator-section, than at the points midway between said front and rear faces, so that increased radiating and cooling surfaces are 80 85 provided.

In order to construct radiator-sections of the general character herein set forth, and to assemble any number of such sections in the form of a complete radiator having a 90 maximum radiating or cooling surface with relation to a minimum space occupied by a radiator, and to provide radiator-sections having no soldered or otherwise connected joints or parts, it is necessary that each 95 radiator-section must be made in one integral piece, and that the various wall-portions of the sections must be extremely thin; and, furthermore, the various diagonal ducts and the laterally extending openings in each 100 section being so closely located, that it will be impossible to produce a radiator-section of this type by the ordinary method of casting, the method employed is necessarily by the electro-deposition of metal, such as 105 copper or other electrolytically deposited metal.

One method or manner of producing such electrolytically deposited structure is described in my former application for Letters-Patent filed April 10th, 1909, Serial Number 489,178, and briefly is as follows: Into a suitable mold of steel, iron, or other suitable material, I pour an easily fusible metal or alloy, the melting point of which 110 is below the boiling point of water, so as to produce a solid metal core, formed with a multiplicity of holes or openings, conforming to the general shape and configuration of the radiator-section desired. After removing the metal pattern, which has thus been produced, from the mold, the same is suspended, as a cathode, in an electroplating bath of the proper density and temperature. A deposit of copper, or other suitable metal, 115 is thereupon made upon the surfaces of the said pattern; and, after a deposit of the required thickness has been made upon said alloy-pattern, so as to form a skin or envelop about the same, the plated pattern or 120 125 130

section is removed from the electro-plating bath and thoroughly cleaned by washing. The interior alloy-core is then removed by the melting-out process, by placing the electroplated alloy-pattern in boiling water or steam, in a suitably heated vessel, taking care that the said electroplating alloy-pattern is held in the water in such a manner, that the melting metal-alloy will be entirely removed, with the result that a complete and hollow or chambered radiator-section or element of the general construction shown in the accompanying drawings is produced. In order to bring any suitable number of such electrolytically deposited radiator-sections into their securely assembled relations, so as to provide a radiator and at the same time connecting therewith a suitable means for conveying the hot water from an engine to and into the radiator-sections for cooling; and, furthermore, to provide means for conveying the cooled water from the radiator back to the engine, devices or means of the general construction shown more particularly in Figs. 4 and 5 of the drawings may be employed. These devices may be respectively termed the inlet and outlet devices.

Referring now to Fig. 4 of the drawings, the said inlet-device consists, essentially, of a pipe-like structure 24 having a screw-threaded opening 25 for the connection therewith of the usual hot water-conveying pipe 26 coming from the engine. The said pipe-like structure 24 terminates at its ends in two pipe-like members or elements 27, each member or element 27 being formed with a flange, as 28. The said members or elements, as will be seen from an inspection of said Fig. 4 of the drawings, extend into and through the aligned tubular members or elements 16 of the assembled radiator-sections, and each pipe-like member or element 27 is furthermore provided with annular depressions 29 formed with suitable holes or perforations 30 which provide channels for a rapid circulation of the hot water and outlets through which the hot water, coming through the structure 24 and the elements 27, flows and passes through the inlets 17 in the elements 16 directly into the space 8 and then through the ducts 10 and 11 of the assembled radiator-sections, and there to be cooled. As shown, the said members or elements 27 are externally screw-threaded; as at 31, the several radiator-sections being held together by the flanges 28, and suitable nuts 32, 33 and 34 which are screwed upon said screw-threaded portions 31, suitable gaskets or flexible washers 35 being also, preferably used so as to produce tight joints.

The outlet device, as will be seen from an inspection of Fig. 5 of the drawings, consists, essentially, of a pipe-like structure 36 having a screw-threaded opening 37 for the

connection therewith of the return-pipe 38 through which the cooled water is returned to the engine. The said pipe-like structure 36 has connected therewith, at its ends and at the middle, three pipe-like members or elements 39, each member being formed with a flange 40. The said members or elements 37, as will be seen from an inspection of said Fig. 5, extend into and through the aligned tubular members or elements 18 of the assembled radiator-sections, and each pipe-like member or element 39 is further provided with annular depressions 41 for rapid circulation of the cooled water, and being further formed with suitable holes or perforations 42 which provide inlets through which the cooled water, flowing from within each radiator-section through the outlets 19 will pass, and will then flow through said elements 39 into the structure 36 and then through the return-pipe 38 back to the engine. The said members or elements 39 are also externally screw-threaded, as at 43, the several radiator-sections being further held together by the flanges 40, and suitable nuts 44, 45 and 46 which are screwed upon said screw-threaded portions 43, suitable gaskets or flexible washers 47 being also preferably used so as to produce tight joints.

Of course it will be understood, that a filling device is also provided, as shown more particularly in Fig. 3 of the drawings, this device or means consisting of a pipe-like member or element 48 which is inserted in the aligned members or elements 20, substantially as shown. At its one end-portion the said member 48 is made with an elbow 49 formed with a mouth or pouring-in opening which may be closed by means of a suitable cap or closure 50. Within the said mouth there may be placed a suitable strainer, as 51, and the said elbow 49 has extending therefrom an extension or lip 52 which engages the upper surface of the radiator-section, and hence helps to retain the pipe-like member or element 48 in its proper place. The said member or element 48 is also provided with annular depressions 53 formed with suitable holes or perforations 54 which provide outlets for the water into and through the inlets 21 of the members or elements 20. The member or element 48 is also externally screw-threaded, as at 55, and is secured in place by means of nuts 56 and 57, suitable gaskets or flexible washers 58 being also preferably used. Other flexible washers or gaskets 59 and metal washers 60, if desired, may be slipped upon the said pipe-like member or element 48 in the spaces formed between the adjacent radiator-sections, as will be clearly evident and as illustrated in said Fig. 3 of the drawings. The said member or element 48 may be provided with a suitable overflow-pipe 61, substantially as shown.

The assembled radiator-sections, of which there may be any desirable number, may be placed in suitable frame-like members 62 and 63, which are suitably connected by 5 means of screws 64, or other suitable fastening devices, the member 63 being suitably flanged, as at 65, for securing the entire device upon the frame-work of an automobile, or to any other fixture.

10 From the foregoing description it will be seen, that a radiator, and radiator-sections therefor, have been produced in which all the parts of each section are made in one integral piece, thereby avoiding the great 15 cost of assembling a great many small parts and the securing together of such parts by means of solder. A hollow or chambered radiator-section is also produced having the interior thereof studded with a great many 20 hollow members which are very closely placed together, and which extend from and form integral portions of the side-walls of the radiator-section, so that the interior of each section is formed with a multiplicity of 25 closely located water-conveying ducts, and with a multiplicity of intermediately placed air-ducts leading from one side to the other side of the radiator-section, and thereby providing a maximum radiating surface.

30 I claim:

1. A radiator for automobiles and the like, comprising a plurality of radiator-sections, each section being made in the form of a chambered casing with a multiplicity 35 of hollow elements and arranged to provide interiorly disposed water-conducting passages surrounded at the top and bottom, as well as at the sides within said casing, with water-spaces, said hollow elements providing the said radiator-section with a multiplicity of ventilating and cooling ducts staggered between said water-conducting passages, tubular elements within the upper and lower water-spaces of said casing, said 40 tubular elements being provided with perforations, and an upper inlet pipe and a lower outlet pipe, each having perforations and an annular depression registering with the perforations of the tubular elements respectively in the upper and lower water-space of the casing.

2. A radiator for automobiles and the like, comprising a plurality of radiator-sections, each section being made in the form 55 of a chambered casing with a multiplicity of hollow elements and arranged to provide interiorly disposed water-conducting passages surrounded at the top and bottom, as well as at the sides within said casing, with 60 water-spaces, said hollow elements providing the said radiator-section with a multiplicity of ventilating and cooling ducts staggered between said water-conducting passages, tubular elements within the upper and

lower water-spaces of said casing, said tubular elements being provided with perforations, an upper inlet pipe and a lower outlet pipe, each pipe having perforations and an annular depression registering with the perforations of the tubular elements respectively in the upper and lower water-spaces of the casing, and a series of tubular stays within said upper and lower water-spaces of the casing.

3. A radiator for automobiles and the like, comprising a plurality of radiator-sections, each section being made in the form of a chambered casing with a multiplicity of hollow elements and arranged to provide 70 interiorly disposed water-conducting passages surrounded at the top and bottom, as well as at the sides within said casing, with water-spaces, said hollow elements providing the said radiator-section with a multiplicity of ventilating and cooling ducts staggered between said water-conducting passages, tubular elements within the upper and lower water-spaces of said casing, said tubular elements being provided with perforations, an upper inlet pipe and a lower outlet pipe, each pipe having perforations and an annular depression registering with the perforations of the tubular elements respectively in the upper and lower water-spaces of the casing, another set of tubular elements in the upper water-space of said radiator-sections, said tubular elements being formed with perforations, and a filling pipe extending into said last-mentioned tubular elements, said pipe being formed with annular depressions having perforations registering with the perforations in said last-mentioned tubular elements.

4. A radiator for automobiles and the like, comprising a plurality of radiator-sections, each section being made in the form of a chambered casing with a multiplicity of hollow elements and arranged to provide 95 interiorly disposed water-conducting passages surrounded at the top and bottom, as well as at the sides within said casing, with water-spaces, said hollow elements providing the said radiator-section with a multiplicity of ventilating and cooling ducts staggered between said water-conducting 100 passages, tubular elements within the upper and lower water-spaces of said casing, said tubular elements being provided with perforations, an upper inlet pipe and a lower outlet pipe, each pipe having perforations and an annular depression registering with the perforations of the tubular elements respectively in the upper and lower water-spaces of the casing, a series of tubular stays within said upper and lower water-spaces of the casing, another set of tubular elements in the upper water-space of said radiator-sections, said tubular elements being

formed with perforations, and a filling pipe extending into said last-mentioned tubular elements, said pipe being formed with angular depressions having perforations registering with the perforations in said last-mentioned tubular elements.

In testimony, that I claim the invention

set forth above I have hereunto set my hand this 28th day of February, 1910.

FREDERICK A. FELDKAMP.
